UNITED STATES PATENT OFFICE.

CHARLES DAVID BONSALL, OF PARNASSUS, PENNSYLVANIA, ASSIGNOR TO UNION METAL PRODUCTS COMPANY, OF CHICAGO, ILLINOIS, A CORPORATION OF DELAWARE.

CAR-WALL STRUCTURE.

Original application filed September 26, 1925, Serial No. 58,845. Divided and this application filed December 3, 1926. Serial No. 152,494.

My invention resides in a method of lining the specific type of car wall structure as disclosed in my co-pending application, Serial No. 58,845, filed September 26, 1925, which 5 invention has for its object to provide an all metal car construction of novel character which is unusually strong for its weight and durable throughout, which may be conveniently and economically manufactured 10 and transported, is weather-proof and which possesses certain other desirable and advantageous features to be hereinafter described and claimed. My sheet metal wall structure is applicable to the end or side of box, automobile, gondola, stock or any other type of railway car equipment, the specific wall being made of one or more metallic plates with their meeting sides overlapped and secured together, the overlapped portions being formed to provide members which 15 act as columns to sustain the roof load as beams to resist the thrust of the lading and as stiffeners to prevent buckling of the wall. These beam-columns may be so formed as to 20 provide ventilators or flues from the exterior to the interior of the car. Such ventilation is desirable because it prevents the condensation of moisture in the air within the car which would injure some types of lading. When 25 these columns, beams or corrugations are positioned vertically it is desirable to provide deeper and, therefore, stronger corrugations adjacent the middle of the car than elsewhere because the greatest stresses are 30 at that place. When the beams or corrugations are positioned horizontally it is desirable to provide deeper and, therefore, stronger corrugations adjacent the floor of the car because the greatest stresses are 35 at that place. When deeper beams are used and the lining is placed inside of them, either the inside length of the car is decreased or the train length is increased. An object 40 of my invention is to provide a method and arrangement of lining for such an end or side wall of a railway car which does not increase the thickness of the wall.

These reinforcements or corrugations may be rectangular, as illustrated, or circular, or of any other desired contour.

In the drawings:

Fig. 1 shows the end of a railway car with my improved wall applied thereon.

Fig. 2 is a section on line 2-2 of Fig. 1.

Fig. 3 is a section on line 3-3 of Fig. 1. 55

Fig. 4 shows a modified form.

For convenience, I have shown an end wall of a box car wherein 1 is the end sill; 2 the end plate and 3 the corner post.

The wall illustrated comprises a plurality of metallic plates 10, 11 and 12, some of which have one or more inwardly projecting corrugations 13-20 which terminate within the lower edge but extend to the upper edge of the plate and others of which 60 have one or more outwardly projecting corrugations 14 which terminate within the upper edge but extend to the lower edge of the plate. These corrugations are positioned opposite each other and the plates are secured together on both sides of the corrugations so as to form a box girder. The corrugation 14 on the outside of the wall is open at the bottom and closed at the top 65 while the corrugation 13 on the inside of the wall is of reverse formation, i. e., closed at the bottom and open at the top, thus forming a ventilating communication between the exterior and interior of the car. 70

The wall may be made of a pair of corrugated plates 15-16 or 17-18 each having a small flange on each side of the corrugation, which flanges are secured together to form a beam-column and flat plates 19 are inserted between the flanges and spans the 75 distance between the respective beam-columns. Such a construction is shown in Fig. 4. 80

However, my arrangement is adaptable to various types of corrugated or embossed 90 metallic walls for railway cars.

In my arrangement I place the lining boards 21 within the bounding planes of the end wall, with the inside of the lining flush with the inside of the deeper beams 13-17 95 so that the thickness of the wall is not increased. This is accomplished by terminating the lining 21 on both sides of the deeper beams or corrugations 13-17 and securing it to the wall in any convenient manner. 100 When a plurality of beams or corrugations are used they are preferably made of different depths for reasons heretofore mentioned, in which case some of the beams (13-17) are of such depth that they are 105 flush with the inside of the lining (that is, the side towards the inside of the car) while other beams or corrugations (15-20) are

shallower and of such depth that they are flush with the outside of the lining. The shallower beams support the lining against horizontal thrust.

5. Nailing strips 27 are secured to the end wall by bolts 26 and are the same depth as the shallower beams. The lining is nailed or otherwise secured to these strips.

10. This is a division of my co-pending application Serial No. 58,845, filed September 26, 1925.

I claim:

15. 1. In a railway car, the combination of a metallic wall plate and a wooden lining spaced therefrom, said metallic plate provided with different depth corrugations, some of which are flush with the inside of said lining, and others of which are flush with the outside of said lining.

20. 2. In a railway car, the combination of a metallic wall plate and a wooden lining spaced therefrom, said metallic plate provided with different depth corrugations, some of which are flush with the inside of said lining, and others of which are flush with the outside of said lining, and timbers secured to said plates to which the lining is attached.

25. 3. In a railway car, the combination of a

metallic wall plate, a wooden lining on the 30 inside of said wall, said wall plate having corrugations flush with the inside of said lining, and means to secure said lining to said wall.

4. In a railway car, the combination of a 35 metallic wall plate and a wooden lining spaced therefrom; said metallic wall provided with relatively deep vertical corrugations adjacent the middle of the wall which are flush with the inside of the lining, said metallic wall also provided with other relatively shallow vertical corrugations which are flush with the outside of the lining.

5. In a railway car, the combination of a 40 metallic wall plate and a wooden lining spaced therefrom; said metallic wall provided with relatively deep vertical corrugations adjacent the middle of the wall which are flush with the inside of the lining, said metallic wall also provided with 45 other relatively shallow vertical corrugations which are flush with the outside of the lining, and nailing strips secured to the wall between said corrugations which are the same depth as the shallower corruga- 50 tions.

CHARLES DAVID BONSALL.
